(57) **CLAIM**

The ornamental design for an immuno-chromatography inspection machine as shown and described.

DESCRIPTION

FIG. 1 is a top, front, right perspective view of an immuno-chromatography inspection machine, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a cross-sectional view of the immuno-chromatography inspection machine of FIG. 1, taken in the direction of line 8-8 in FIG. 4; and,

FIG. 9 is a cross sectional view of the immuno-chromatography inspection machine of FIG. 1, taken in the direction of line 9-9 in FIG. 6.

The equal-length broken lines in the drawings depict portions of the immuno-chromatography inspection machine that form no part of the claimed design. The dash-dot-dash broken lines define the bounds of the claim. All broken lines form no part of the claimed design.
